UNITED STATES PATENT OFFICE.

SOLOMON SMITH, OF RAVENNA, OHIO, ASSIGNOR OF TWO-THIRDS TO JOHN J. LIGHTCAP AND JOHN E. ALBRIGHT, OF RAVENNA, OHIO.

MACHINE FOR FORMING BALL-SHAPED OR SPHERICAL BODIES.

SPECIFICATION forming part of Letters Patent No. 694,330, dated February 25, 1902.

Application filed May 10, 1901. Serial No. 59,677. (No model.)

To all whom it may concern:

Be it known that I, SOLOMON SMITH, a resident of Ravenna, in the county of Portage and State of Ohio, have invented certain new and useful Improvements in Machines for Forming Ball-Shaped or Spherical Bodies; and I do hereby declare the following to be a full, clear, and exact description of the invention, such as will enable others skilled in the art to which it pertains to make and use the same.

My invention relates to improvements in machines for forming ball-shaped or spherical bodies, and especially well adapted for forming marbles from chunks or pieces of argillaceous or other material having sufficient plasticity or the consistency required to render them capable of being manipulated and formed into the shape of balls or spheres.

The primary object of this invention is to construct a machine of the character indicated which is exceedingly simple in construction and reliable in its operation, which has a large capacity, which does its work with great facility or rapidity, and which is capable of forming various sizes of balls or spheres.

With this object in view and to the end of realizing other advantages hereinafter appearing the invention consists in certain features of construction and combinations of parts hereinafter described, and pointed out in the claims.

In the accompanying drawings, Figure I is a side elevation, in central vertical section, of a machine embodying my invention. Figs. II and III are vertical sections on line II II and line III III, respectively, Fig. I, looking inwardly. Fig. IV is a view in perspective of a chunk or piece of plastic material, which piece constitutes a blank upon which my improved machine is adapted to operate. Fig. V illustrates a ball or sphere resulting from the operation of my improved machine upon the blank shown in Fig. IV.

Referring to the drawings, *a* designates a rotary upwardly and downwardly extending cylinder arranged in an inclined plane and operatively mounted in any approved manner upon a horizontally-arranged or approximately horizontally arranged shaft *b*, which may be supported in any approved manner and is provided with a driving-pulley *c*. The

cylindrical shell *a'* of the cylinder *a* has each end thereof cut, preferably vertically or approximately so, and provided with a flange *a''*, 55 formed externally of the said shell and extending circumferentially of the said shell in a vertical plane. The cylinder *a* is provided at each end with a head *e*, which is riveted or otherwise rigidly secured to the adjacent 60 flange *a''* and has a centrally-located opening *e'* for receiving the plastic blanks which are to be formed into balls or spheres within the cylinder. The heads *e* close the ends of the outer circumferential portion of the chamber 65 of the shell *a* and form, therefore, internal rims for the ends of the cylinder. Each head *e* is provided upon its outer side with a cross-bar *f*, which is arranged radially and centrally of the said head and is rigidly secured 70 to the head in any approved manner. The cross-bars *f* of the two cylinder-heads are preferably parallel and are provided with registering and corresponding holes *f'*, through which the shaft *b*, upon which the cylinder 75 is mounted, extends. Operative connection between the cylinder and the shaft is established by the well-known means of groove and feather, as at *g*, or in any other approved manner. Each cross-bar *f* is preferably provided with another shaft-receiving hole *f''*, 80 located a short distance longitudinally of the said bar from the hole *f'* of the bar. The holes *f''* and *f'* of the two bars *f* are formed at opposite sides, respectively, of the shaft-line 85 extending through the holes *f'* and register, so that the cylinder is placeable at more than one angle relative to the shaft, being arranged at a greater or less angle to the shaft, according as it is mounted upon the shaft at 90 the holes *f'* or at the holes *f''*.

The driving-pulley *c* of the machine is shown operatively connected by a belt *c'* with a pulley *d* of a counter-shaft *d*.

The blank which is to be operated upon 95 may be cylindrical or almost a cube, as shown in Fig. IV. The exact form of the blank is immaterial. A finished ball or sphere capable of being formed by my improved machine is shown in Fig. V.

The operation of my improved machine will be readily understood. The blanks in a suitably plastic state are introduced into the cylinder *a* at the opening *e'* in one or both rim-

forming heads e of the cylinder, whereupon the cylinder is rotated. A speed of about twenty-five rotations per minute has been found very practical. The blanks operated upon are held against the internal peripheral surface of the cylinder by centrifugal force. The blanks move twice from end to end and longitudinally of the cylinder in opposite directions alternately during each rotation of the cylinder, because each end of the cylinder is alternately the lowest and highest portion of the inclined cylinder during the rotation of the cylinder. Thousands of blanks may be operated upon at one and the same time if the cylinder is large enough. The blanks being operated upon roll during the rotation of the cylinder in every conceivable direction, are fairly well formed in a few minutes, and perfect balls or spheres can be formed in half an hour or less, according to the speed at which the cylinder is rotated. The material composing the blanks operated upon is also rendered somewhat more dense during the operation upon the blanks. The sizes of the blanks to be operated upon is immaterial, because the balls or spheres formed within the cylinder can be readily as sorted as to size. Obviously large balls or spheres for ornamental, architectural, or other purposes or marble-forming small balls or spheres can all be formed by my improved machine.

The shell a' of the cylinder a is provided at one end and preferably in close proximity to the head e of the said end with a lateral aperture a^3 , at which the balls or spheres formed within the cylinder are discharged from the cylinder. The aperture a^3 is normally closed by a door h , which is suitably hinged, as at h' , to the shell a , and upon its outer side is provided, as shown in Figs. I and II, with an ordinary spring-bolt k , normally in its operative position, wherein it engages a hole a^4 , formed in the adjacent flange a^2 , and is retained in the said position by its suitably-applied spring l . (See Fig. I.) By actuating the bolt k against the action of the spring l out of engagement with the hole a^4 when the door-carrying portion of the shell a' is in position constituting the lower portion or bottom of the cylinder the door h opens by gravity to accommodate the escape of the finished balls or spheres from within the cylinder. I would remark also that the openings e' in the rim-forming heads of the cylinder accommodate the passage of air through and thereby ventilate the cylinder.

What I claim is—

1. A machine for forming ball-shaped or

spherical bodies, comprising an upwardly and 60 downwardly extending inclined cylinder having heads cut away centrally to form holes for receiving bodies or blanks to be operated upon, and two cross-bars arranged centrally and radially of and rigid with the different 65 heads, respectively, and the cylinder being rotatably supported at the said cross-bars and having its axial line arranged horizontally or approximately horizontally, substantially as and for the purpose set forth. 70

2. A machine for forming ball-shaped or spherical bodies, comprising an upwardly and downwardly extending inclined cylinder provided, at the ends, with heads cut away centrally to form holes for receiving bodies or 75 blanks to be operated upon, cross-bars extending across the said holes and rigid with the heads, means for rotating the cylinder comprising a horizontally-arranged or approximately horizontally arranged shaft extending through the cylinder and through the aforesaid bars, means establishing operative connection between the said cross-bars and the shaft, and means for rotating the shaft, substantially as and for the purpose set forth. 80 85

3. A machine for forming ball-shaped or spherical bodies, comprising a horizontally-arranged or approximately horizontally arranged shaft and an upwardly and downwardly extending inclined cylindrical shell 90 operatively mounted upon the shaft and provided, at the ends, with internal rims extending circumferentially of the cylinder around the shaft, substantially as and for the purpose set forth. 95

4. A machine for forming ball-shaped or spherical bodies, comprising an upwardly and downwardly extending inclined cylinder having heads cut away centrally to form holes for receiving blanks or bodies to be operated 100 upon, and two cross-bars arranged centrally and radially of and rigidly secured to the outer side of the different heads, respectively, means for rotating the cylinder and comprising a horizontally-arranged or approximately horizontally arranged shaft extending through the cylinder and through the aforesaid bars; means establishing operative connection between the said cross-bars and the shaft, and means for rotating the shaft, substantially as and for the purpose set forth. 105 110

Signed by me at Ravenna, Ohio, this 4th day of May, 1901.

SOLOMON SMITH.
